A. D. WINN

COMBINED TONGUE AND SHOE LACE FASTENER

Filed June 18, 1926

UNITED STATES PATENT OFFICE.

ADELBERT D. WINN, OF TORONTO, ONTARIO, CANADA.

COMBINED TONGUE AND SHOE-LACE FASTENER.

Application filed June 18, 1926. Serial No. 116,920.

My invention relates to improvements in that form of shoe fastening means which provides for the holding of the shoe tongue in a definite centralized position. It is the 5 primary object of the invention to provide a novel means whereby both the tongue and laces will be held against slipping even should the shoe laces become untied.

The invention also contemplates a very 10 simple arrangement of this character which will be readily applicable to both high and low shoes with but a minimum of expense.

The foregoing and other features of novelty will be readily appreciated upon reading 15 the following description of the now preferred embodiment of the invention which is disclosed in the accompanying drawing forming a part of this specification. I am aware that various changes may be 20 made in the structure as disclosed without departing from the invention as claimed hereinafter.

In the drawings,

Figure 1 is a perspective view of a shoe 25 incorporating my invention, the lacing being loosened to better illustrate the relative arrangement of the tongue eyelet or openings to the eyelets or openings of the upper;

Fig. 2 is an elevation showing the rear 30 side of the tongue illustrated in Fig. 1 with the lacing applied;

Fig. 3 is a perspective view showing a 35 slightly different relative arrangement of the lacing, and

Fig. 4 is a perspective view of a shoe showing a slightly modified form of the invention 40 wherein the shoe tongue is provided with two eyelets through which the laces are passed before being put through the last of the shoe upper eyelets.

Referring specifically to the drawings, 45 wherein similar reference characters have been used to designate like parts in all views, numeral 1 indicates the shoe upper which is provided with eyelets 2, and reference character 3 designates the shoe tongue. In Figs. 1, 2 and 3 the shoe tongue 3 is seen as being 50 provided with four eyelets in rectangular or square formation. The upper pair of eyelets are designated by reference characters 4 and 5, respectively, while the lower pair are designated by reference characters 6 and 7, respectively. There is provided centrally of the square designed by the eyelets afore-

mentioned, an eyelet 8. The usual shoe laces 55 are indicated by 9 and 10.

In the arrangement of Fig. 1, it is observed that the lace 9 is passed through the shoe tongue eyelet 6 from the outside thereof, and is pulled out from beneath the tongue 60 through the eyelet 8 from whence it is led to the top eyelet 2 at the right hand side of the shoe upper as viewed in Fig. 1. The other lace 10 is inserted inwardly through the shoe tongue eyelet 7 and crosses the lace 65 9 at the site of the central eyelet 8, this latter lace 10 being drawn outwardly through the shoe tongue eyelet 4 and being passed through the top shoe upper eyelet 2 at the left hand side as clearly shown in Fig. 1. 70 The laces 9 and 10 are pulled tight and tied in the usual manner. Obviously the shoe tongue 3 will be held in a central position, and further it will be appreciated that by reason of the binding of the laces 9 and 10 75 in the shoe tongue eyelets the laces will be prevented from slipping. It is especially important in this connection to observe that the lace 10 binds against the lace 9 beneath the tongue at the site of the central eyelet 8 80 to prevent said lace 9 from slipping.

Fig. 3 discloses a different relative arrangement of the laces 9 and 10 with respect to the shoe tongue eyelets. There the lace 10 is passed through tongue eyelet 7 and 85 brought out through the central eyelet 8. Lace 9 passes inwardly through tongue eyelet 6 and is brought outwardly through tongue eyelet 5 thus crossing the lace 10 at the central eyelet 8. It is seen therefore 90 that each lace by frictional engagement with the tongue eyelets and the tongue will be held against loosening should the shoe become untied. Obviously the laces 9 and 10 may have a relatively different arrangement 95 with respect to the tongue than I have shown. For instance, lace 10 might be passed inwardly through eyelet 8 and out through eyelet 4 while lace 9 might be drawn inwardly through eyelet 6 and outwardly through eyelet 5 crossing lace 10 at central eyelet 8. It also follows that the reverse of the arrangement just described could be followed with lace 9 being passed through eyelets 8 and 5 and lace 10 through 100 eyelets 7 and 4, the laces crossing at eyelet 8 as usual.

It will be appreciated that the advantage

of the variable arrangement of lacing with respect to the tongue enables the wearer to shift the position of the laces from time to time so that they will not be uncomfortable and perhaps cause the foot to get sore.

In Fig. 4 it is seen that the tongue 12 is formed with but two eyelets 13 which are in horizontal spaced relation and are disposed slightly below the top eyelets 14 of the shoe upper 15. After passing each lace 16 through both tongue eyelets 13, they are passed through the top eyelets 14 of the shoe upper and subsequently tied. Thus, should the laces become untied the binding of the said laces in the eyelets will prevent them from coming loose. In both forms of the invention the pressure of the foot of the wearer against the tongue and laces and also the binding of the laces against one another and in their eyelets will prevent their becoming loose.

A shoe formed with my invention may if desired be worn as a slipper in that the laces

need not be tied, but may simply be pulled up and tucked in the sides of the shoe.

Having thus described my invention what I claim as new and desire to secure by Letters Patent is:

In a shoe, the combination of a tongue having a plurality of openings therein defining a square and having a central opening within the square so defined and equidistant from each of said openings, laces for binding the shoe upon the foot, said laces being insertible through different combinations or sets of said tongue openings whereby to hold the said laces in crossed relation and against slipping should the shoe laces become untied, the laces binding in said openings and between the tongue and the foot of the wearer to be thereby held in place.

In testimony whereof I affix my signature.

ADELBERT D. WINN.
